UNITED STATES PATENT OFFICE.

ROBERT HENRY KLINGEL, OF BRIDGEPORT, CONNECTICUT, ASSIGNOR TO
THE HOLMES & EDWARDS SILVER COMPANY, OF SAME PLACE.

DESIGN FOR A HANDLE FOR TABLE-WARE.

SPECIFICATION forming part of Design No. 19,276, dated August 20, 1889.

Application filed July 24, 1889. Serial No. 318,556. Term of patent 14 years.

To all whom it may concern:

Be it known that I, ROBERT HENRY KLINGEL, a citizen of the United States, residing at Bridgeport, in the county of Fairfield and State of Connecticut, have invented a certain new and useful Design for Handles for Table-Ware, of which the following is a specification.

This invention relates to a design for the handles of spoons, forks, and other articles of table-service; and it consists in the ornamentation of the surface of the shank and blade of the handle, as hereinafter described, and shown in the accompanying illustration.

From the bowl of the spoon the handle extends in the form of a narrow shank A, and on the face of the latter are formed curved ribs or crescents *a*, between which are radiating lobes *b*, said lobes gradually diminishing in size as they approach the edges of the shank.

B is the blade of the handle, having a rib *c* formed on its edges and a short rib *d* at about the junction of the shank and blade. Above the shank the handle is ornamented by two

scroll-like lines *e*, turning outwardly at their lower ends and inwardly at their upper ends, and the space between said two scroll-like lines has smaller scrolls, as shown, together with a central lobe *h* and diminishing beads *i*. Without the said two scrolled lines, above their lower ends, upon each side thereof, is a leaf *k*, with diminishing beads *l*. Directly below the ends of the scroll-like lines are other lobes and beads, as indicated, respectively, by the letters *m* and *n*.

The leading features of my design are the curved ribs or crescents and radiating lobes alternating on the face of the shank.

I claim—

A design for handles for spoons, forks, and other articles of table-service, substantially as herein shown and described.

In testimony whereof I have signed my name to this specification in the presence of two 45 subscribing witnesses.

ROBERT HENRY KLINGEL.
